US0D1001614S

(12) **United States Design Patent** (10) **Patent No.:** **US D1,001,614 S**
(45) **Date of Patent:** **** Oct. 17, 2023**

(54) **APPLIANCE DOOR HANDLE**

- (71) Applicant: **WHIRLPOOL CORPORATION**,
Benton Harbor, MI (US)
- (72) Inventors: **Suzanne M. Berberet**, St. Joseph, MI
(US); **Quinn Chintis**, Ferndale, MI
(US); **Michael C. Lah**, Benton Harbor,
MI (US); **John J. Myers**, Saugatuck,
MI (US); **Lauren Szczesny**, St. Joseph,
MI (US); **Jason W. Tippets**,
Stevensville, MI (US)
- (73) Assignee: **WHIRLPOOL CORPORATION**,
Benton Harbor, MI (US)

(**) Term: **15 Years**

(21) Appl. No.: **29/754,019**

(22) Filed: **Oct. 6, 2020**

Related U.S. Application Data

- (62) Division of application No. 29/641,331, filed on Mar.

(57) **CLAIM**

The ornamental design for an appliance door handle, as shown and described.

DESCRIPTION

FIG. 1 is a front perspective view of an appliance door handle according to the design;

FIG. 2 is a front perspective detail view of area 2 indicated in FIG. 1;

FIG. 3 is a front elevation view of the appliance door handle of FIG. 1;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The portions of the article shown in even-dash broken lines form no part of the claimed design. The dash-dot broken lines in FIGS. 1-2 represent the bounds of the detail view and form no part thereof.

1 Claim, 5 Drawing Sheets
